DESIGN FOR A FROZEN CONFECTION

John W. West, Maplewood, N. J., assignor, by
mesne assignments, to Good Humor Corpora-
tion of America

Application February 11, 1933, Serial No. 47,191

Term of patent 14 years

To all whom it may concern:

Be it known that I, JOHN W. WEST, a citizen of the United States, and resident of Maplewood, in the county of Essex and State of New Jersey, have invented a new, original, and ornamental Design for a Frozen Confection, shown and described in the following specification and the drawing, forming a part thereof.

In the drawing Figure 1 is a front perspective view of a frozen confection showing my new design;

Fig. 2 is an end view;

Fig. 3 is a sectional view along the line 3—3 of Fig. 1; and

Fig. 4 is a sectional view along the line 4—4 of Fig. 1.

The design is that of a body of generally conical shape from the apex of which a stick-like handle projects. Two opposite sides of the conical body are cut away to form two plane surfaces extending from the base part way to the apex and substantially parallel to each other and to the major axis of the cone. Elsewhere the conical surface remains unaltered.

I claim:

The ornamental design for a frozen confection, as shown and described.

Signed at New York in the county of New York and State of New York this 9th day of February A. D. 1933.

JOHN W. WEST.
